Primary Examiner — Freda S Nunn(74) *Attorney, Agent, or Firm* — Umberg Zipser LLP;
 Ryan S. Dean(57) **CLAIM**

The ornamental design for an overhead display, as shown and described.

DESCRIPTION

FIG. 1 is a front, bottom, left side perspective view of an overhead display of the new design.

FIG. 2 is a front elevation view of the overhead display of FIG. 1.

FIG. 3 is a rear elevation view thereof.

FIG. 4 is a left side elevation view thereof.

FIG. 5 is a right side elevation view thereof; and,

FIG. 6 is a bottom plan view thereof.

The broken lines in the Figures are included for the purpose of defining the claim boundary, and form no part of the claimed design.

1 Claim, 4 Drawing Sheets(56)
